Inventor
Thomas A. Conlon

By W. W. Poach.

Attorney

UNITED STATES PATENT OFFICE.

THOMAS A. CONLON, OF SILVER SPRING, MARYLAND.

LOADER FOR GUNS.

Application filed February 19, 1925. Serial No. 10,340.

(GRANTED UNDER THE ACT OF MARCH 3, 1883; 22 STAT. L. 625.)

The invention described herein may be used by the Government, or any of its officers or employees in prosecution of work for the Government, or by any other person in the 5 United States, without payment to me of any royalty thereon, in accordance with the act of March 3, 1883.

The subject of this invention is a loader for guns.

10 When guns, especially of the anti-aircraft type, are maintained in high elevation to permit rapid firing the problem of ramming heavy projectiles into the gun requires that mechanical assistance be resorted to.

15 The present invention contemplates the provision of a traveling rammer mounted on the loading tray and actuated to advance the round into a gun by means of a cable which is trained over pulleys.

20 To these and other ends, my invention consists in the construction, arrangement, and combination of elements, described hereinafter and pointed out in the claim forming a part of this specification.

25 A practical embodiment of my invention is illustrated in the accompanying drawing, in which,

Fig. 1 is a view in side elevation of a loader constructed in accordance with the invention; and

Fig. 2 is a transverse sectional view through the apparatus, the tray being shown in the inward or ramming position.

35 Referring to the drawing by numerals of reference:

A tray 5 on which the round is placed preparatory to loading it into the gun is secured to a pair of bent arms 6-6 which are mounted for oscillatory movement on 40 the cradle 7 of the gun. The usual handle

8 is provided on one of the arms for moving the apparatus to position the round in line with the bore of the gun.

Attached to the tray 5 is a rail 9 upon which is mounted by means of rollers 10-10 45 a traveling rammer 11, having a bent finger 12 extending over an edge of the tray and adapted to engage behind the round. Secured to the rammer is a cable 13 trained over a pulley 14 and guide rollers 15-15 50 and provided with a handle or grip 16. The forward extremity of the rail terminates in a toe 17 which limits the forward movement of the rammer while a stop 18 is also provided on the rear end of the rail for a similar purpose. After advancing a round into the chamber of the gun the rammer is 55 manually withdrawn by means of the handle 19, which may also be used in lieu of the cable to advance the rammer.

60 While in the foregoing there has been illustrated and described such combination and arrangement of elements as constitute the preferred embodiment of my invention, it is nevertheless desired to emphasize the 65 fact that interpretation of the invention should only be conclusive when made in the light of the subjoined claim.

I claim:

In combination with a gun, a loading tray 70 mounted for oscillatory movement on the cradle thereof, a rail on the tray, a rammer movable on the rail and having a finger extending within the tray for engaging a projectile, means on the rail for limiting 75 movement of the rammer, a cable attached to the rammer, pulleys over which the cable is trained, and a handle for moving the rammer.

THOMAS A. CONLON.
